US0D1094751S

(12) **United States Design Patent** (10) Patent No.: **US D1,094,751 S**
(45) Date of Patent: ** Sep. 23, 2025

(54) HAIR REMOVAL DEVICE

(71) Applicant: **Shanghai Haier Medical Technology Co., LTD**, Shanghai (CN)

(72) Inventors: **Zhihong Gao**, Shanghai (CN); **Zun Yu**, Shanghai (CN); **Zhenwei Song**, Shanghai (CN); **Mingyue Meng**, Shanghai (CN)

(73) Assignee: **Shanghai Haier Medical Technology Co., LTD**, Shanghai (CN)

(**) Term: **15 Years**

(21) Appl. No.: **29/997,561**

(22) Filed: **Apr. 8, 2025**

(51) LOC (15) Cl. **28-03**

(52) U.S. Cl.

USPC **D24/209**
